O. ALTBENBACH

COMBINED SCISSORS AND SHOEHORN

Filed May 9, 1927

INVENTOR.

OTTO ALTBENBACH

BY *Munn & Co.*

ATTORNEY.

UNITED STATES PATENT OFFICE.

OTTO ALTBENBACH, OF LOS ANGELES, CALIFORNIA.

COMBINED SCISSORS AND SHOEHORN.

Application filed May 9, 1927. Serial No. 190,049.

My invention relates and has for a purpose the provision of a pair of scissors constructed so as to provide the additional function of a shoe-horn to facilitate the placing 5 of shoes on the feet.

It is also a purpose of my invention to provide an instrument of the above-described character which accomplishes the dual functions recited without impairing the manual 10 operation and proper functioning of the device as a pair of scissors, yet permitting it to be used as an instrument for facilitating the insertion of the feet into shoes with the same degree of success as the conventional 15 shoe-horn.

I will describe only one form of combined scissors and shoe-horn embodying my invention and will then point out the novel features thereof in a claim.

20 In the accompanying drawings, Fig. 1 is a view showing in top plan, one plan of combined scissors and shoe-horn embodying my invention;

Fig. 2 is a view showing the instrument in 25 edge elevation;

Fig. 3 is a transverse sectional view taken on the line 3—3 of Fig. 1; and

Fig. 4 is a view showing the instrument in rear end elevation.

30 Referring specifically to the drawings, my invention in its present embodiment comprises an instrument which primarily consists of a pair of scissors, it being made up of a pair of blades 15, crossed and pivoted at 35 the point indicated at 16 to allow relative movement of the blades for cutting. Beyond the pivot point 16, the blades merge into handles 17 provided with finger receiving openings 18.

40 As clearly illustrated, the handles 17 have their outer edges rounded, while their inner edges are flat in order to permit the blades 15 to lie one on the other when in closed position.

The handles 17 are curved transversely 45 and slightly longitudinally at their free ends, the two handles co-operating to form when in close position a substantially heart-shaped body of concavo-convex contour to simulate the contour of the nose or leading 50 end of a shoe-horn. Thus in practise the handles when closed provide a body which will function in the same manner as the conventional shoe-horn when applied to a shoe to facilitate the insertion of the foot into 55 the shoe. In practise the blades 15 function as a handle for the shoe-horn and are gripped and held in close position while the shoe-horn end of the instrument is applied to the foot. The handles 17 when not employed as a shoe-horn, function in a normal 60 manner to receive the fingers and permit manipulation of the blades as in cutting.

Although I have herein shown and described only one form of combined scissors 65 and shoe-horn embodying my invention, it is to be understood that various changes and modifications may be made herein without departing from the spirit of the invention and the spirit and scope of the appended 70 claim.

I claim as my invention:

Scissors having their blades terminating in handles having straight abutting edge portions extending along a longitudinal line 75 with the blades when the latter are closed, the handles being offset from the blades so that when the edges are in relative abutment the respective sides of the handles are flush with each other, the said handles mutually 80 describing a heart-shaped body when the blades are closed, and the said handles being curved transversely and longitudinally so that the body is concavo-convex.

OTTO ALTBENBACH.
